UNITED STATES PATENT OFFICE.

THOMAS ELLISON, OF ABINGDON, ILLINOIS.

FIRE-FENDER.

SPECIFICATION forming part of Letters Patent No. 374,951, dated December 20, 1887.

Application filed May 31, 1887. Serial No. 239,902. (No model.)

To all whom it may concern:

Be it known that I, THOMAS ELLISON, a citizen of the United States, residing at Abingdon, in the county of Knox and State of Illinois, have invented certain new and useful Improvements in Fire-Fenders; and I do hereby declare the following to be a full, clear, and exact description of the invention, such as will enable others skilled in the art to which it applies to make and use the same, reference being had to the annexed drawings, making a part of this specification, and to the letters and figures of reference marked thereon.

The object of this invention is to prevent the spread of fire from one section of a block or building to another; and it consists of pieces of sheet-iron bolted together and placed between the walls of two adjacent houses, so that if one house should take fire the fender can be projected to prevent the blaze and heat from damaging the adjoining building.

Referring to the drawings, Figure 1 is a perspective view with the fender closed. Fig. 2 is a plan view of the fender, and Fig. 3 a perspective with the fender pulled out.

A A represent two adjacent buildings; B B, a space between the buildings, in which my fender is located.

C C C are chains or rods for manipulating the fender.

D D represent the fender, which is shown projected in Fig. 3.

E represents a bolt or stop in the end of a prolongation of the fender to prevent the end of the fender passing the supporter I and guide-wheel.

F represents a recess in the front face of the wall for the reception of the block L.

On the front edge of the fender G G show two tracks on which the device runs.

H represents a supporter over the wall through which the fender passes when projected.

I shows a rear supporter in which one of the guide-wheels is located, the guide-wheel running upon the top of the fender D and rudder or guide J.

K K show the side guide-wheels.

N N show the inner edge of the fender when projected.

O O represent the inner edge of fender when projected.

P P represent the two short supporters.

J represents an extension rearward of the top of the fender, which acts as a guide or rudder.

My fender is made of good hard sheet-iron, the length of the sheets to correspond to the width of the fender, riveted together to reach from the top of the wall to about four feet from the base of the buildings. These sheets are bound all around with wrought-iron. A piece four inches wide is placed on each side of the top of the fender and long enough to extend rearward and form the rudder or prolongation J. The fender and the two side pieces are bolted together from one end to the other and make the fender five-eighths inch thick at the top. A piece of band-iron two inches wide and one-fourth inch thick is bolted on each side in front, with holes to receive the chains C C C. The rear edge and bottom of fender is bound with a piece of light band-iron. The axle of the guide-wheel K is placed through the top of the fender at such a location that there will always be as much as two and one-half feet of the fender remaining in between the walls when projected. A round bar of iron should be used for the tracks.

The supporters H and I should be of heavy band-iron, and bolted to the tracks. The supporters P P should be of a lighter grade of iron. Supporter I extends down on each side of the wall eight to ten feet, and is bolted through the wall with three or four bolts, making it sufficiently strong to stay the fender.

The trucks or wheels are made of cast-iron, not less than six inches in diameter and three inches thick, with a round groove in each wheel, the height of wheels depending upon the length of the fender.

A block of buildings made of incombustible material provided with a fender placed on the corner of each building will make that block secure from fire.

In use, project the fender on the side of the fire, the firemen placing themselves on the opposite side from the fire, throwing water on the fender and holding it firm to its place.

My device acts on the principle that an ounce of preventive is worth a pound of cure.

Where there are two buildings joining, one of incombustible material the other not, my device is advantageous.

What I claim as new, and desire to secure by Letters Patent, is—

1. A device to prevent the spread of fire from one section of a block or building to another, consisting of a movable metallic plate or wall, a space or pocket between the sections, 5 and means for moving said plate or wall into or out of said space.
2. The combination, with the building provided with the described space, of a movable fender provided with stops to limit its movement, substantially as described.
3. The combination, with a metallic plate or fender movable within a space between two sections of a building, of a rearward prolongation or guide at the top of the fender, for the 15 purpose substantially as set forth.
4. The combination, with the building provided with the described space, of a movable

fender provided with stops to limit its movement, one stop being upon the front edge of the fender and adapted to rest in a recess on 20 the wall of the building to support the fender while at rest, substantially as described.

5. The combination of supporters H and I, wheels K K, tracks G G, small supporters P P, and chains C C C, adapted to hang down in 25 the space of the wall in front of the fender and be ready at all times for operation, all substantially as set forth.

In testimony whereof I affix my signature in presence of two witnesses.

THOMAS ELLISON.
